UNITED STATES PATENT OFFICE

156,286

DESIGN FOR A THERMOSTATIC SWITCH

Norman J. Smith, Medfield, Mass.

Application October 15, 1948, Serial No. 149,139

Term of patent 7 years

(Cl. D26—13)

To all whom it may concern:

Be it known that I, Norman J. Smith, a citizen of the United States, residing at Medfield, in the county of Norfolk and Commonwealth of Massachusetts, have invented a new, original, and ornamental Design for Thermostatic Switch, of which the following is a specification, reference being had to the accompanying drawing, forming part thereof.

Figure 1 is a front elevational view of a thermostatic switch, showing my new design;

Figure 2 is a plan view of a thermostatic switch; and

Figure 3 is an end elevational view of a thermostatic switch.

I claim:

The ornamental design for a thermostatic switch, as shown.

NORMAN J. SMITH.
